A. PÜRRER

PIANO ACTION OR MOVEMENT

Filed Nov. 11, 1924

Anton Pürrer,
INVENTOR:

By *Attn:*
his ATTORNEY.

UNITED STATES PATENT OFFICE.

ANTON PÜRRER, OF KLOSTERNEUBURG, AUSTRIA.

PIANO ACTION OR MOVEMENT.

Application filed November 11, 1924. Serial No. 749,130.

To all whom it may concern:

Be it known that I, ANTON PÜRRER, a subject of the Republic of Austria, residing at Klosterneuburg, Austria, have invented 5 new and useful Improvements in Piano Actions or Movements, of which the following is a specification.

This invention relates to improvements in piano-actions or movements with one-armed 10 key-levers, which are jointed at one end.

According to the present invention hooked 15 guide-members are arranged between the individual key-levers, which not only prevent a lateral adjustment of the keys, but also serve as pivots for the hammer-shafts jointed to the key-levers.

Two modes of carrying out the present invention are shown by way of example on the accompanying drawing in which,

20 Fig. 1 is a part-sectional side-view of an action for pianos with horizontally disposed strings.

Fig. 2 is a part-sectional side-view of an 25 action for pianos with upright strings, and

Fig. 3 is a section taken on line A—B of Fig. 1.

In the illustrated embodiments the articulated connection between the key 1 and the hammer-seat 3, as well as between the hammer-joint 4 and the hammer-shaft 6 is established by means of parchment-strips 2 and 5 respectively in order to reduce the cost of manufacture.

However, if desired these articulated connections may be carried out by means of 35 wooden or metal joints or links of the known shape. However, the key 1 may be provided with a separate link and may be screwed to the hammer-seat in order to enable the removal of each individual key.

40 Hooked guide-members 11 are screwed into the frame of the key-board between the individual key-levers, so that the keys cannot strike against each other when playing 45 on the piano.

According to the present invention the key 1 is in the shape of a quite freely floating trap-lever to which the flat hammer-shaft 6, formed with the hammer-head in 50 one piece, is screwed by means of its hammer-joint 4, so that the cloth covered end 7 of the hammer-shaft rests on the hooked guide-member 11 and the hammer-head 8 upon the hammer-cushion 13.

55 The position of the keys may be regulated

in height by screwing in or out the hooked guide-members, while the play of the piano-action or movement can be regulated according to requirement by means of bending forwardly or backwardly the hooked guide-members and the fall or drop of the keys and the degree of lifting the hammer can be adjusted by means of the stop-ledge 29 and 30 respectively. The vibration of the hammer-head 8, after striking the key, is 60 prevented by the catch-lever 27 or 25, which is screwed into the hammer-shaft 6, cooperating with the cushion 28 or 26 secured to the corresponding hammer-joint 4.

Extensions 14 screwed to the rear end of 65 the key 1 and a lifting projection 24 serve for raising the damper 18 or 23 respectively.

According to the present invention the striking of the hammer is effected in a most simple manner without the provision of a 70 push-tongue or push-lever hitherto necessary in all high-class actions or movements. On depressing the key 1, the rear end of which is jointed to the hammer-seat 3, the hammer-joint 4 is simultaneously pulled 75 down and therefore the hammer-shaft 6, resting with its cloth-covered end 7 on the hooked guide-member 11, and thus also the head 8 are flung against the string 32 and during the backward movement are immediately caught by the catch-levers 27 and 25 respectively, thus preventing any vibration of the same.

I claim:

1. A piano action comprising one-armed 90 key-levers, guide members between the levers to prevent lateral motion thereof, and hammer shafts articulated to the key-levers and designed to encounter the guide members as fulcrums when the levers are depressed. 95

2. A piano action as claimed in claim 1, said guide members having hooked portions overlying the key-levers and designed to be encountered by said hammer-shafts. 100

3. A piano action comprising a key-lever 105 fulcrumed at its rear end, a hammer shaft flexibly jointed thereto, and a guide member adjacent the key-lever to prevent lateral motion of the latter and having a portion overlying the lever designed to be encountered as a fulcrum by the hammer shaft when the key-lever is depressed.

In testimony whereof I have signed my name to this specification.

ANTON PÜRRER.
